FIG. 3 INVENTOR:
Joseph Mader
by *Joseph Mader*
ATTORNEY

UNITED STATES PATENT OFFICE

2,305,019

MOMENTUM TOP

Joseph Mader, Albany, N. Y.

Application July 29, 1939, Serial No. 287,262

1 Claim. (Cl. 46—67)

My invention particularly relates to an amusement device comprising a top and a flexible element adapted to be connected to and readily disconnected from said top and twisted about itself to impart rotary movement to the top when connected therewith.

An object of my invention resides in the provision of an amusement device comprising a top, adapted to be spun, a flexible, elongated element which is adapted to be twisted upon itself and untwisted to spin the top, and means for connecting said elongated element in a zone intermediate the length thereof to said top whereby rotary movement or spinning of the top may be produced by twisting and untwisting the elongated element upon itself, and said means being characterized by the fact that it may readily be actuated by inertia to disengage the top and flexible, top-spinning element while the top is rotating or spinning.

Further objects of my invention reside in providing an amusement device of the foregoing character in which means for connecting the top with the elongated element are provided and which comprise, in one embodiment, an element frictionally engageable with the top; in a second embodiment, screw threaded means; and in a third form, an element frictionally and resiliently engageable with the top.

With these and other objects in view, my invention includes the novel elements and the combinations and arrangements thereof described below and illustrated in the accompanying drawing, in which—

Fig. 1 is an elevation view of one form of my invention showing the top and top-spinning device in disengaged relationship;

Fig. 2 is a view similar to Fig. 1 but showing a modified form of connecting means; and

Fig. 3 is a fragmentary view, generally similar to Fig. 1 but showing another modified form of connecting means.

Generally speaking, my invention contemplates providing a top, adapted to be spun or rotated with such rapidity that it will spin about a vertical axis through its pointed end, and a means which is operable to impart such rapid spinning movement to said top and which may be readily disconnected therefrom.

In the embodiment of my invention illustrated in Fig. 1, the amusement device indicated generally at 1 comprises a top 2 and a top-spinning device 3. The spinning device 3 comprises a flexible, elongated element 4 which may be formed, for example, of cord or similar somewhat

extensible material which will twist upon itself as illustrated in the drawing when stressed in tension and then relieved. To the cord 4 and in a zone intermediate the length thereof is fastened a connecting element 5 which, in the embodiment illustrated, comprises a frusto-conical plug through a laterally extending opening in which the element 4 may be passed as indicated at 6. The top 2 is provided with a centrally disposed recess 7, preferably slightly tapered, which is adapted to receive the plug 5. The plug when inserted within the recess 7 will be frictionally engaged by the walls thereof to a degree sufficient to impart rotary movement from the plug to the top 2, the walls of the recess 7 and plug 5 constituting a means or a cooperable means for connecting the top with the spinning device 3 and it will be understood that, due to the inertia of the top, the plug 5 may be readily jerked from the recess 7 while the top is spinning so as to free or entirely disengage the top from the spinning device.

The top 2 may be provided with the usual metal, pointed tip 8 upon which it spins and, if desired, the ends of the element 4 may be fastened in bead-like or generally spherical elements 9 which serve to prevent the element 4 from slipping between the fingers when the device is being operated.

To spin the top, the plug 5 is first wedged in the recess 7 in the top and, thereafter, by successively applying tension to the element 4, for example, by grasping it with the hands adjacent the beads 9 and pulling the ends thereof in opposite directions, and then relieving the tension by moving the hands toward each other, the element 4 is caused to twist upon itself as shown in the drawings. This operation is continued until the top spins at a sufficiently high velocity whereupon the top-spinning device 3 may be disengaged from the top while it is spinning by pulling or snapping the plug 5 out of the recess 7.

In Fig. 2, I have shown a modified form of my invention in which the top 2a is generally similar to the top 2 and the top-spinning device 3a is generally similar to that shown at 3 in Fig. 1 and comprises the flexible elongated element 4. However, a modified means is employed for connecting the top-spinning device with the top for imparting spinning or rotary movement thereto. In this embodiment, the top 2a is provided with an upstanding cylindrical stud 10 which is secured thereto in any suitable manner and arranged with its axis substantially coinciding with the axis of the top. The stud 10 is screw threaded as indi-

cated at 10' and adapted to be threaded into a threaded recess 11 in a plug-like element 12 which may be fastened to the flexible element 4 substantially in the same manner as illustrated in Fig. 1.

To operate this embodiment of my invention the plug-like element 12 is first threaded upon the stud 10 and rotary movement of the element 12 and top 2a is produced by successively tensioning and relieving the tension on the flexible element 4 as in the manner of operation of the device of Fig. 1. When sufficient spinning velocity is attained, the element 4 may be tensioned and temporarily held under tension thereby suddenly preventing any substantial further turning of the plug 12 while the top 2a, continuing its spinning, will, due to its inertia, cause the stud 10 to unscrew from the plug 12 and thereby disengage the top, assuming, of course, that the top and plug were spinning in a clockwise direction as viewed from above when further turning of the plug was so arrested.

In Fig. 3, I have shown a further modified form of connecting means for imparting movement from the flexible element 4 to the top. In this embodiment, the flexible element 4 is provided with a resilient connecting means indicated generally at 13 which may be formed of a wire bent to form a loop 14 through which the flexible element 4 is passed, as illustrated, when the ends of said wire extending outwardly and downwardly in spaced relation as indicated at 15 and 16. Normally the arms occupy the positions illustrated in full lines but may be resiliently compressed toward each other as indicated in dotted lines.

The top 2b is provided with a pair of recesses 17 and 18 which are so spaced apart that the arms 15 and 16 of the resilient connecting element 13 must be compressed in order to be inserted therein. When so inserted, the arms being resiliently urged apart, will engage the side walls of the recesses 17 and 18 and serve to connect the top with the flexible element 4.

To spin the top 2b, it is merely necessary to in-

sert the arms of the resilient connecting element 13 into the recesses provided in the top therefor and to produce spinning movement thereof through an operation of the element 4 as hereinbefore described. When sufficient speed has been developed, the top may be freed by snapping or pulling the arms of element 13 out of the recesses in the top.

It will be noted that the amusement device of my invention is inexpensive in construction and simple to operate so that enjoyment, in operating it, may be derived by children even of very immature age.

While I have described my invention in its preferred embodiments, it is to be understood that the words which I have used are words of description rather than of limitation. Hence, changes within the purview of the appended claim may be made without departing from the true scope and spirit of my invention in its broader aspects.

What I claim is:

In a device of the character described, the combination with a top having axially extending recesses therein, of a spinning means therefor comprising a single, flexible, elongated element adapted to be twisted about itself, and means secured to said element intermediate the ends thereof and comprising arms resiliently movable toward and away from each other and adapted resiliently to be urged into engagement with the walls of said recesses frictionally to fasten said spinning means to said top, whereby said top may be carried by and suspended from said element, said arms being movable in a direction axially of said top by a jerk on said flexible element to separate said top and spinning means; the frictional engagement of said last mentioned means in said recesses alone being sufficient to permit a spinning movement to be imparted to said top but insufficient to prevent disengagement thereof from said recesses by applying a jerk to the spinning means thereby employing the inertia of said top to disengage said top and spinning means.

JOSEPH MADER.
